MANIFOLDING

William G. Borchers, Hoboken, N. J., assignor to
 Autographic Register Company, Hoboken, N. J.,
 a corporation of New Jersey

Application June 8, 1940, Serial No. 339,419

12 Claims. (Cl. 282—12)

This invention relates to manifolding, and, more particularly, to a record strip for use in a manifolding machine of the kind having means for feeding a plurality of continuous strips over a writing platen, means for arresting advancement of the strips at form-length intervals, and for maintaining the strips in registration.

For proper coaction with said means, previous record strips have been provided with feed-arresting form-registering physical alterations placed at form-length intervals along said strip. Such alterations in each form length were constituted by a plurality of apertures within the strip, that is, intramarginal apertures, or by cut-away portions or notches along the margins thereof; and similarly said alterations were intersected by transverse severing lines between successive form lengths, or spaced apart from such severing lines, lying wholly within each form length. In each case, however, the said alterations in each form length were arranged in transverse alignment to cooperate with the feeding mechanism in a manifolding machine to arrest each form length as it reached a predetermined position on the platen.

However, as disclosed in my copending application Serial No. 339,418, filed June 8, 1940, the provision of one set of transverse aligned apertures in each form length cooperating with feeding means of a manifolding machine to arrest advancement of the strip when each form length reaches a predetermined position is not efficient in some circumstance to effect accurate registration of the superposed strips both in transverse as well as longitudinal direction, for instance, when the various strips are of different weight or of different surface characteristics. Under these circumstances, the strips are also subject to overthrow beyond the desired stopping position, bringing a severing line between two successive form lengths beyond a severing station on the machine at which it is generally desired to sever certain of the issued form lengths of the strips. This effect is aggravated by variations in the manner of operating the machine, some operators using a slow steady motion for feeding the strips, others using a relatively rapid jerky motion. Tensioning means provided to retard advancement of the strips is not entirely effective to avoid this disadvantage.

Accordingly, in my aforesaid copending application I have disclosed a manifolding register provided not only with a main feeding means co-operating with one set of physical alterations in multiple manifolding strips, to arrest feeding of

the stationery before a severing line between two successive form lengths reaches a predetermined severing station on the machine, but also with an auxiliary feeding means to resume advancement of the strips to move the said feed-arresting physical alterations beyond the bite of said main feeding means, and cooperating with a second set of feed-arresting form-registering physical alterations to arrest further advancement of the strips by the time the said severing line reaches the said severing station on the machine. Means is also provided to release the superposed strips temporarily from engagement with the main feeding means while the auxiliary feeding means engages the physical alterations aligned therewith, whereby the latter means is effective to accurately reregister the superposed strips with each other by the time the said severing line reaches said severing station.

My said invention disclosed in my companion application, it will be appreciated, embraces not only the structure of the mechanism for feeding the strips, but also the structure of the strips themselves, the latter being claimed in this application.

A feature of the present invention is the provision of a multiple manifolding strip comprising marginal as well as intramarginal feed-arresting form-registering physical alterations, especially a strip in which the marginal feed-arresting alterations are positioned in advance of the intramarginal feed-arresting form-registering physical alterations.

Another feature is the provision of a record strip of the aforesaid type, having severing lines at form-length intervals, wherein one set of feed-arresting form-registering alterations is intersected by said lines, and a second set of feed-arresting form-registering apertures is spaced apart from said weakened severing lines and contained wholly within each form length of the strip, especially a strip wherein the marginal alterations are intersected by the aforesaid severing lines and the intramarginal alterations are disposed within the strip.

And still a further feature is the provision of a multiple manifolding strip having weakened severing lines at form-length intervals, wherein the forward boundary of one set of feed-arresting form-registering physical alterations coincides with said severing lines while a second set of feed-arresting physical alterations is provided to the rear of the first-named set of alterations.

As shown, a multiple manifolding strip is provided having transverse severing lines formed in

the usual manner between each successive form length of the strip, and having two sets of feed-arresting form-registering physical alterations in each form-length, differing mutually as to their longitudinal as well as transverse alignment in the strips.

Preferably, one set of alterations is intersected by the transverse severing lines, whereby tearing of the strips along said lines is facilitated, and the 10 folding of the strips in a zigzag folded pile is likewise rendered more convenient.

One set of feed-arresting form-registering alterations is adapted to cooperate with the main feeding means of a manifolding machine while a 15 second set, positioned to the rear of the first set for each form length, is adapted to cooperate with an auxiliary feeding means.

The set of physical alterations adapted to cooperate with the auxiliary feeding means is preferably positioned closer to the longitudinal axis 20 of the strip, the other set of alterations being positioned adjacent to the margins thereof. By this means, the main feeding means of the manifolding machine engages the strip adjacent its 25 margins, and thus tends to retain the strips against lateral displacement during the main feeding operation. Furthermore, re-registration of the superposed strips by the auxiliary feeding means engaging the auxiliary feed-arresting alterations adjacent the center of the strip eliminates any bulging of the strips which may 30 occur during the main feeding operation.

The feed-arresting physical alterations adapted to cooperate with the main feeding means of 35 the manifolding machine are preferably formed as triangular cutaway portions or notches along the margins of the strips. There is considerable saving in the manufacture of such forms. For 40 example, when pairs of intramarginal openings are formed, six punches and dies are required for a triplicate job, that is, one in which there are three superposed forms in a set of strips, whereas with marginal notches, due to the location 45 thereof, punches and dies would be in the form of a triangle, and for the same triplicate job only four would be required across the strip.

The forward boundary of one set of feed-arresting physical alterations is preferably formed 50 coincident with the transverse severing lines. Folding of the strips in a zigzag pile is facilitated thereby, and longitudinal registration of the superposed strips, when such alterations are engaged by one of the feeding means, is more accurate, since the feeding means engages the forward edge of the strips at right angles to the direction of advancement, and hence has no tendency to displace the strips laterally.

The auxiliary feed-arresting form-registering 55 physical alterations are preferably formed as apertures within the body of each form-length whereby they may be used for filing form lengths issued from the machine.

Further features and advantages will appear 60 from the following description, referring to the accompanying drawing which illustrates one embodiment of the present invention, that at present preferred.

70 In the said drawing:

Figure 1 is a perspective view of a zigzag folded pile of a plurality of superposed record strips according to the present invention.

Fig. 2 is a plan view showing a portion of a 75 single continuous record strip, being one of the

plurality of superposed strips making up the pile shown in Fig. 1.

Referring to the drawing, the manifolding strip of the present invention comprises a plurality of superposed continuous record strips, 5 each divided into a series of form lengths 10a, 10b and 10c, as illustrated in Fig. 2, by transverse weakened severing lines 11, constituted for instance, by a series of perforations.

Each form length is provided with a pair of feed-arresting form-registering marginal notches 12 symmetrically disposed at opposite sides of each form length, and aligned transversely across the form. As shown in the drawing, the notches 12 are intersected by the transverse severing lines 15 11 at their apex whereby the severing of said forms along said line is facilitated, no matter how slight the said line is weakened. Furthermore, as shown, the leading edges 13 of the said notches form an extension of the severing lines 11, while 20 the trailing edges 14 of said notches are contained wholly within each successive form length. The provision of leading edge 13, as shown, which is normal to the direction of the feed, improves 25 registration of the superposed strips in longitudinal direction when the forward boundary of the notch is engaged by a feeding means adapted to cooperate therewith, reducing any tendency of 30 the strip to bulge up in the center.

The foregoing arrangement of the said notches 35 also aids and facilitates to a maximum degree the folding of the strips into a zigzag pack as shown in Fig. 1.

In each of the form lengths, a pair of auxiliary 40 transversely aligned feed-arresting form-registering alterations are shown comprising a pair of apertures 15 inwardly spaced with reference to the 45 margins of the strip and positioned to the rear of the aforesaid transverse severing lines 11. Thus, the apertures 15 differ in alignment with the notches 12 in transverse as well as longitudinal direction. The said apertures 15 may be suitably formed and spaced to adapt the form lengths after issuing from the machine to be fastened together by suitable filing means.

As shown in Fig. 1, a plurality of superposed 50 strips are preferably folded zigzag fashion along the transverse weakened lines 11 to form a pack 16.

As hereinbefore set forth, the notches 12 are 55 adapted to cooperate with the main feeding means of a manifolding register as described in my copending application Serial No. 339,418, filed June 8, 1940, to arrest feeding of the superposed strips and bring them into longitudinal alignment before a severing line 11 between two successive form lengths reaches a predetermined severing station on the machine.

The auxiliary apertures 15 are adapted to 60 cooperate with an auxiliary feeding means, transversely aligned with the said main feeding means, to arrest the advancement of the strips after the feed has been resumed by said auxiliary feeding means, whereby the notches 12 are brought beyond the bite of the main feeding means, and to accurately reregister the superposed strips in longitudinal as well as transverse direction by the time one of the severing lines 11 has reached 65 the aforesaid tearing station.

As hereinbefore indicated, the notches 12 may 70 be formed with their leading edges 13 extending into the preceding form length instead of coinciding with the tear-off lines 11. Furthermore, it is not necessary that the feed-arresting form- 75

registering alterations adapted to cooperate with the main feeding means be formed as notches. They may, if desired, be formed as apertures within the margins of the strips differently aligned from a second set of apertures 15 adapted to cooperate with auxiliary feeding means. Similarly, the latter set of apertures may be positioned, if desired, adjacent the margin of the strip, while the first-named apertures may be provided within the body of the strip spaced further away from the margins thereof. One or both of said sets of feed-arresting form-registering alterations may be spaced apart from the transverse severing lines 11, suitable modifications in the spacing of the tear-off station from the feeding means in the machine being made.

Variations and modifications may be made within the scope of this invention and portions of the improvements may be used without others.

20 I claim:

1. A manifolding pile comprising a plurality of continuous record strips in superposed relation, all of the strips having weakened transverse severing lines at form-length intervals, and having two sets of feed-arresting form-registering physical alterations similarly located in each form length; one set of said alterations being intersected by said severing lines, the other set being spaced apart from said severing lines; the two sets differing as to longitudinal alignment, and being adapted respectively to cooperate with a main feeding means and an auxiliary feeding means in a manifolding register with which the strips are to be used.

2. A manifolding pile comprising a plurality of continuous record strips in superposed relation, all of the strips having weakened transverse severing lines at form-length intervals, and having two sets of feed-arresting form-registering physical alterations similarly located in each form length; one set of said alterations being formed by cutaway portions along the margins of said strips intersecting the said severing lines; the other set of alterations being formed within the body of the strip spaced apart from said severing lines said sets of alterations being adapted respectively to cooperate with a main feeding means and an auxiliary feeding means in a manifolding register with which the strips are to be used.

3. A manifolding pile comprising a plurality of continuous record strips in superposed relation, all of the strips having weakened transverse severing lines at form-length intervals, and having two sets of feed-arresting form-registering physical alterations similarly located in each form length; the forward boundaries of one set of said alterations coinciding with the transverse severing lines, the other set positioned to the rear of the first-named set of alterations in different longitudinal alignment on the strips; both sets lying wholly within the form lengths of the strip, and adapted respectively to cooperate with a main feeding means and an auxiliary feeding means in a manifolding register with which the strips are to be used.

4. A manifolding pile comprising a plurality of continuous record strips in superposed relation, all of the strips having weakened transverse severing lines at form-length intervals, and having two sets of feed-arresting form-registering physical alterations similarly located in each form length; one set of said alterations being formed by triangular notches along the margin of said strips, the apex of which notches are

intersected by the transverse severing lines, the other set of alterations comprising apertures lying wholly within each form-length of the strip spaced apart from said severing lines; said sets of alterations being adapted respectively to cooperate with a main feeding means and an auxiliary feeding means in a manifolding register with which the strips are to be used.

5. A manifolding pile comprising a plurality of continuous record strips in superposed relation, all of the strips having weakened transverse severing lines at form-length intervals, and having two sets of feed-arresting form-registering physical alterations similarly located in each form length; one set of said alterations being formed by triangular notches along the margins of said strips, the forward boundaries of which notches coincide with said severing lines, the other set of alterations comprising apertures lying wholly within each form length of the strips, said sets of alterations being adapted respectively to cooperate with a main feeding means and an auxiliary feeding means in a manifolding register with which the strips are to be used.

10 6. A manifolding pile comprising a plurality of continuous record strips in superposed relation, all of the strips having weakened transverse severing lines at form-length intervals, and having two sets of feed-arresting form-registering physical alterations similarly located in each form length; the alterations of each set being arranged in symmetrical pairs transversely across said strips, one set of said alterations being formed by cutaway portions along the margins of the strips intersecting the aforesaid severing lines, the other set of alterations being formed by apertures lying wholly within each form length of the strips, said sets of alterations being adapted respectively to cooperate with a main feeding means and an auxiliary feeding means in a manifolding register with which the strips are to be used.

15 7. A manifolding pile comprising a plurality of continuous record strips in superposed relation, all of the strips having weakened transverse severing lines at form-length intervals, and having two sets of feed-arresting form-registering physical alterations similarly located in each form length; one set of said alterations being formed by a pair of notches symmetrically disposed at the margins of said strip in each form length, the apex of said notches being intersected by the aforesaid transverse severing lines; and the other set comprising a pair of apertures lying wholly within each form length symmetrically disposed transversely of said strip and spaced apart from the said transverse severing lines; the sets of alterations being adapted respectively to cooperate with a main feeding means and an auxiliary feeding means in a manifolding register with which the strips are to be used.

20 8. A manifolding pile comprising a plurality of continuous record strips in superposed relation, all of the strips having weakened severing lines at form-length intervals and having two sets of feed-arresting form-registering physical alterations similarly located in each form length; one set of alterations being formed by a pair of triangular notches symmetrically disposed at the margins of the strips in each form length thereof, the forward boundaries of said notches coinciding with the transverse severing lines between successive form lengths; the other set of alterations

- comprising pairs of apertures symmetrically disposed transversely of said strips lying wholly within each form length to the rear of said transverse severing lines, the said sets of alterations being adapted respectively to cooperate with a main feeding means and an auxiliary feeding means in a manifolding register with which the strips are to be used.
9. A zigzag folded pile of manifolding stationery comprising a plurality of superposed continuous record strips, all of the strips having weakened transverse severing lines at form-length intervals, and having two sets of feed-arresting form-registering physical alterations similarly located in each form length; one set of said alterations being intersected by the weakened severing lines between successive form lengths, the other set of alterations lying wholly within each form length, spaced apart from said severing lines, and differing as to longitudinal alignment with the first set of alterations; the said sets of alterations being adapted respectively to cooperate with a main feeding means and an auxiliary feeding means in a manifolding register with which the strips are to be used.
10. A zigzag folded pile of manifolding stationery comprising a plurality of superposed continuous record strips all of the strips having weakened transverse severing lines at form-length intervals, and having two sets of feed-arresting form-registering physical alterations similarly located in each form length; the forward boundaries of one set of said alterations coinciding with the said transverse severing lines, the other set of alterations being positioned to the rear of the first set, and comprising apertures lying wholly within the form lengths, spaced apart from said severing lines; said sets of alterations being adapted respectively to cooperate with a main feeding means and an auxiliary feeding means in a manifolding register with which the strips are to be used.
11. A manifolding pile comprising a plurality of continuous record strips in superposed relation, said strips having two sets of feed-arresting, form-registering physical alterations at form-length intervals, one of said sets being formed by cutaway portions along the margins of said strips, and the other set being longitudinally aligned and inwardly spaced from said margins, said sets differing mutually as to transverse alignment, and being adapted respectively to cooperate with a main feeding means and an auxiliary feeding means in a manifolding register with which the strips are to be used.
12. In a manifolding pile comprising a plurality of continuous record strips in superposed relation, said strips having two adjacent sets of feed-arresting, form-registering physical alterations at form-length intervals, one of said sets being formed by cutaway portions along the margins of said strips, and the other set being longitudinally aligned and inwardly spaced from said margins, said sets differing mutually as to transverse alignment, and being adapted respectively to cooperate with a main feeding means and an auxiliary feeding means in a manifolding register with which the strips are to be used, adjacent marginal and intra-marginal alterations within each form-length being disposed with the latter alterations to the rear of the former.

WILLIAM G. BORCHERS.
